M. CARABALLO.
AUXILIARY AIR VALVE FOR GAS ENGINES.
APPLICATION FILED OCT. 20, 1916.

1,251,962.

Patented Jan. 1, 1918.

UNITED STATES PATENT OFFICE.

MARTIN CARABALLO, OF TAMPA, FLORIDA.

AUXILIARY AIR-VALVE FOR GAS-ENGINES.

1,251,962.

Specification of Letters Patent.

Patented Jan. 1, 1918.

Application filed October 20, 1916. Serial No. 126,720.

To all whom it may concern:

Be it known that I, MARTIN CARABALLO, a citizen of the United States, residing at Tampa, in the county of Hillsborough and State of Florida, have invented certain new and useful Improvements in Auxiliary Air-Valves for Gas-Engines; and I do hereby declare the following to be a full, clear, and exact description of the invention, such as will enable others skilled in the art to which it appertains to make and use the same.

The present invention relates to new and useful improvements in auxiliary air valves for gas engines of the type in which an air supply is connected to the intake of an internal combustion engine between the carbureter and engine cylinders for supplying additional air to be mingled with the fuel mixture prepared by the carbureter, and thus diluting such fuel mixture to a degree that is controlled by said air valve.

It is the primary object of the present invention to provide such air valve under the automatic control of the throttle-actuating mechanism to automatically dilute the fuel mixture by the addition of the auxiliary air when the engine speed increases and when the throttle is opened wider to permit the entrance of a proportionately larger charge of the fuel.

Another object of the present invention lies in providing an improved device of the character above specified in which the individual parts will be simple and the device, as a whole, of simplified construction and operation; and in which there is provided an improved air valve structure and improved connection for coupling the air valve to the throttle controlling mechanism.

In the accompanying drawings forming a part of this application, and in which similar reference symbols indicate corresponding parts in the several views:

Figure 1 is a side elevational view of an engine shown as equipped with an auxiliary air valve constructed in accordance with my invention, and which latter is shown partly in section.

Fig. 2 is an enlarged sectional view of the improved air valve construction.

Fig. 3 is a perspective view of the connection between the air valve and throttle mechanism; and

Fig. 4 is a perspective view of one form

of an elbow used in connecting the air valve to the engine intake pipe.

Referring more particularly to the drawings, any approved type of internal combustion engine is indicated at 1 in Fig. 1, the same being equipped with the usual intake and exhaust manifolds 2 and 3, respectively. The exhaust manifold 3 connects in the usual manner with the exhaust pipe 4; while the intake manifold 2 is connected by the intake pipe 5 with the carbureter designated at 6, which prepares the mixture in the usual manner.

In accordance with the present invention, an auxiliary valve is connected at any point between the carbureter 6 and the engine cylinders 1, it being advantageously fitted in the intake pipe 5 substantially at the point shown in Fig. 1. The connection of the air device with the intake pipe 5 is preferably made by an elbow 7, which is shown more particularly in Fig. 4 as having one end 8 threaded for the purpose of screwing into said intake pipe 5; said elbow 7 having its other end 9 formed with a bayonet slot 10, or other coupling means, through which the casing or shell of the air valve is attached thereto.

The air valve is more particularly disclosed in Fig. 2, where it is seen to comprise a shell or casing 11 having a reduced end 12 forming a shoulder 13 which furnishes a seat for a cylindrical valve 14. On the reduced end 12 is one or more pins 15 designed to engage the bayonet slots 10 in the elbow 7, whereby a readily removable connection is made between the valve casing 11 and the intake of the engine.

The cylindrical valve 14 is free to reciprocate in the casing 11, and is normally and yieldingly held against its seat 13 by a coil spring 16 which bears, at its outer end, against a cap 17 screw threaded or otherwise removably fitted on the casing 11. The cap 17 has a central perforation through which slidably passes a stem 18 connected to the valve body 14 within the casing 11, and at its outer end is bent at right angles, as indicated at 19, and engaged through a vertically extending slot 20 in the upper end of a lever 21.

This lever 21 is fulcrumed at 22, as by a rivet, screw, or other means, on a bracket 23 formed integral with a hollow stock 24

extending at right angles to the valve casing 11, and advantageously cast in one piece therewith; there being a port 25 establishing communication between the hollow stock 24 and valve casing to admit air from the outside atmosphere in a manner which will be hereinafter more fully explained.

The lower end of the stock 24 is open, and connects with a pipe or flexible tube 26 having a flange 27 engaging and held tightly against the lower end of the stock 24 by a cap nut 28 threaded or otherwise removably secured thereon. A packing or gasket 29 may be interposed between the flange 27 and nut 28, if desired or found necessary.

The flexible tube or pipe 26 runs to a cylindrical or other shaped sleeve 30, embracing the exhaust pipe 4 and having open communication at one or more ends through one or more openings 31 with the outside atmosphere. This sleeve 30 acts in the capacity of a heater for receiving air from the outside atmosphere through the apertures 31, and circulating the same in contact with the heated exhaust pipe 4, through which a higher temperature is imparted to the air; and thereafter such air is delivered through the flexible tube 26 to the stock 24, and through the valve 14 to the intake pipe 5, where it will commingle with the mixture from the carbureter 6.

The lever 21 extends down, as seen in Fig. 1, to the side of and below the operating rod 32 of the throttle 33. This lever 21 is designed to be simultaneously actuated with the throttle 33, and for this purpose I provide the loose connection shown in enlarged perspective in Fig. 3. This connection advantageously consists in a pair of metallic blocks 34 and 35, fitted together and secured as by a screw 36 or other convenient means. The blocks 34 and 35, adjacent their lower ends, are formed with complementary semi-cylindrical channels or grooves 37 and 38, respectively, which, when the blocks are assembled together, unite to constitute a complete circular opening therebetween for receiving and tightly embracing the throttle control rod 32. Through this means a connection is mounted to move with said control rod 32 when the same is shifted in either direction to open wider or cut down the throttle 33.

Between the metallic blocks 34 and 35 is clamped a plate 39 extending beyond said blocks, and having its lower longitudinal edge 40 bent to conform to the curvature of the control rod 32 to assist in holding the connection thereon and to prevent its swinging upwardly. At its outer free end the plate 39 is split or divided, as indicated at 41, and a lug 42 bent therefrom substantially in the manner indicated in Fig. 3, leaving a slot 43 of appreciable depth for loosely receiving the lever 21 in the manner shown

in Fig. 1. There is a circular notch 44 formed in the base of the lug 42 to overlie the control rod 32 and prevent the outer end of the connection from dropping beneath the latter.

A concise description of the operation will suffice to enable those skilled in the art to understand thoroughly the working of the invention.

The control rod 32 is actuated by the operator in the usual manner from the steering column, and by such control rod 32 the throttle 33 is opened or closed and the engine speed is advanced or diminished accordingly. It is desirable that the fuel mixture prepared by the carbureter 6 be diluted with additional air, especially for advanced speeds of the engine, and by the use of air introducing means between the carbureter and engine the fuel consumption has been found to be greatly reduced, and the operating cost of automobiles and other gas engines consequently greatly diminished.

In opening the throttle 33 wider to advance the speed of the engine, the control rod 32 will be moved to the left, and through the loose connection will shift the lever 21, moving its upper slotted end to the right and drawing upon the stem 18 and valve 14. In proportion, therefore, to the opening of the throttle 33, will be the opening movement of the auxiliary air valve 14, which will move to the right in the casing 11 and uncover the port 25 therein; thus placing the stock 24 in open communication with the intake pipe 5. The heated air prepared in the sleeve 30 and admitted to the stock 24 from the flexible tube 26, will thus be drawn into the intake pipe 5 under the influence of the suction of the engine 1, and will commingle with the mixture prepared by the carbureter 6 and dilute such mixture in proportion to the speed on the engine.

When the throttle rod 32 is moved to the right to cut down the speed of the engine, the connection will move away from the lever 21, and in so doing will permit the spring 16 to return the auxiliary air valve 14 to its seat 13, thus reducing or cutting off entirely the additional air supply.

It will be found from the foregoing that I have provided an improved auxiliary air valve together with an improved mechanism for actuating the same automatically from the movement of the throttle control, and that my device is simple in construction and easy and automatic in operation, as also extremely cheap to manufacture and capable of being installed on existing types of gas engine without alteration in construction thereof.

It is obvious that those skilled in the art may vary the details of construction and arrangements of parts without departing from the spirit of my invention, and there-

fore I do not wish to be limited to such features except as may be required by the claims.

I claim:

- 6 1. The combination of a movable element, a valve, a lever connected to actuate said valve, and a loose connection on said movable element engaging said lever to shift the valve, said connection including a plate having a slot for receiving said lever, and means for clamping said plate on said movable element, substantially as described.
- 10 2. The combination of a movable element, a valve, a lever for moving said valve, and a loose connection mounted on said movable element and including a plate having a slot therein for receiving said lever, and blocks clamped over said plate and said movable element, substantially as described.
- 15 3. The combination with an operating rod 20 of a valve, a lever for actuating said valve, a loose connection between said lever and operating rod including a plate having its lower longitudinal edge bent about said operating rod, opposed blocks clamped together on opposite sides of said plate and having recesses therein conforming to said operating rod and received thereby, said plate having a lug cut therefrom and bent to provide a slot for loosely receiving said 25 lever, said lug provided with a slot at one end to engage the lever and move the same when the operating rod is shifted in one direction only, substantially as described.

In testimony whereof, I affix my signature.

MARTIN CARABALLO.
